UNITED STATES PATENT OFFICE.

GEORGE FRANKLYN MATTESON, OF ROCKY HILL, CONNECTICUT, ASSIGNOR TO THE FULLER BRUSH COMPANY, OF HARTFORD, CONNECTICUT, A CORPORATION OF CONNECTICUT.

STOP-MOTION MECHANISM.

Application filed May 2, 1925. Serial No. 27,577.

My invention relates to the class of devices that are employed for stopping the operation of a machine when abnormal conditions arise, and an object of my invention, 5 among others, is to provide a mechanism of this kind that shall be simple in construction and particularly efficient in operation.

One form of mechanism embodying my invention and in the construction and use 10 of which the objects herein set out, as well as others, may be attained, is illustrated in the accompanying drawings, in which—

Figure 1 is a view in side elevation of a mechanism embodying my invention, parts 15 of the machine to which the mechanism is applied being broken away to show construction.

Figure 2 is a view similar to Figure 1, but looking in a direction from a point located 20 at right angles to the point of view of Figure 1.

Figure 3 is a detail view, scale enlarged, in section through a portion of the device on a plane denoted by the dotted line 3—3 of 25 Figure 1.

My invention is particularly applicable to machines embodying reciprocating members in which definite and accurate degrees of movement are required and in which certainty of operation of the stop motion mechanism is essential when a predetermined resistance to the movement of such parts takes place, such conditions being present in a machine in which pieces of metal are moved 30 from one position to another after the operation of dies thereon. Such a machine has, therefore, been selected by me for the purpose of illustration in the drawing herein of mechanism embodying my invention, in which drawings the numeral 5 indicates a portion of the frame of a punch press embodying a 35 table 6 with a bed plate 7 thereon supporting dies 8—9 in connection with which dies 10—11 operate for the purpose of forming 40 pieces of metal. A feed device 12 of any ordinary form of construction is employed for feeding a strip 13 of metal to the dies, in which dies such piece of metal is formed, this mechanism embodying a plunger 14 for 45 moving a formed or partially formed piece of metal from one set of dies to the other, the plunger 14 having a reciprocating movement caused by the feed device 12.

In moving these pieces of metal it is im-

portant that they be accurately positioned, 55 and it is essential that if any material resistance to the movement of the pieces is had the operation of the machine shall be stopped, as undue resistance will cause an operating lever 15 to be broken and in many cases injury to or breaking of the plunger 14 or the dies hereinabove referred to, with a consequent loss of time in replacing the broken or injured parts.

The lever 15 is pivoted at its lower end to a 60 bracket 16 and is operated as by means of a connecting rod 17 engaged with a cam 18 secured to a shaft 19, which shaft may also operate other members of the mechanism and which is connected with other operative parts 65 of the machine including the plunger head 20 to which the dies 10 and 11 are secured. The shaft 19 is driven as by means of intermeshing bevel gears and a connecting shaft 21, shown in dotted outlines in Figure 1 of 70 the drawings, this shaft 21 being driven as by means of a belt passing around a pulley 22. A clutch of any ordinary form and construction is employed for connecting the pulley 22 with the shaft 21, this clutch embodying a clutch member 23, and it is in connection with this clutch member that my improved stop motion mechanism is employed.

This stop motion mechanism comprises a 75 clutch actuating lever 24 operatively connected with the clutch member 23 in any ordinary manner and supported by a rock shaft 25 to which a handle lever 26 for manual operation of the clutch is secured. A stop motion lever 27 is secured to the shaft 25 and 80 is connected by a link 28 with a stop motion arm 29. The link 28 is connected with the lever 27 by means of a pin and slot connection that is such as to permit a movement of the link 28 in the ordinary operation of 85 the machine and independently of the lever 27.

The stop motion arm 29 is pivoted as at 90 30 to the operating lever 15, and this arm is rigidly secured to the connecting rod 17 by 95 means of a stud 31 threaded into the arm 29 and pivotally engaged within an opening in one of the ears of the forked end of the rod 17, and as shown in Figure 3 of the drawings, said arm being, by means of these parts, rigidly connected with the lever 15.

The connecting rod 17 is breakably connected to the operating lever 15 by means of a

shearable pin 32 extending through a bushing 33 in one of the ears of the forked end of the lever 17, through a bushing 34 in the lever 15 and through a hole in the stud 31. This shearable pin 32 is composed of comparatively soft metal, such that it may be sheared off upon application of an abnormal degree of force resisting movement of the feed device 12, and the bushings 33-34 are formed of 10 comparatively hard metal so that shearing off of the pin may readily take place.

It will thus be seen that in the operation of the machine under normal conditions the lever 15 will be moved to and fro and 15 the link 28 will, in this operation, move freely and independently of the stop motion lever 27, but should undue obstruction to movement of the lever 15 occur the pin 32 will be severed thereby permitting the connecting rod 20 17 to be moved by the cam 18 independently of the lever 15 as, when the pin 32 becomes severed, the rigid connection hereinbefore described of the arm 29 with the lever 15 is broken, and thereafter there exists only the 25 pivotal connection of the pivot 30 between said arm and lever. At the same time the connection existing between said arm and the connecting rod 17 comprising the stud 31 causes the arm 29, which has previously been 30 moved contemporaneously with the lever 15, to be swung on its pivot and thereby move independently of said lever, the extent of movement imparted to the lower end of the arm now exceeding that before existing, and being 35 such as to cause engagement of the ends of the slot 35 in the link 28 with the pin in said slot, whereby the stop motion lever 27 is operated to rock the shaft 25 and cause operation of the clutch mechanism to separate the 40 clutch parts and stop operation of the machine.

In accordance with the provisions of the patent statutes I have described the principles of operation of my invention, together with 45 the device which I now consider to represent the best embodiment thereof; but I desire to have it understood that the device shown is only illustrative, and that the invention may be carried out by other means and applied 50 to uses other than those above set out.

I claim:-

1. A stop motion mechanism including a member movable to stop operation of the machine, an operating device, and a connection 55 between said movable member and said operating device, said connection including a member operable independently of said movable member under normal conditions, and a member adapted to move under abnormal 60 conditions to increase the movement of said operable member and thereby cause a stopping movement of said independently operable member.

2. A stop motion mechanism including a 65 member movable to stop operation of the

machine, an operating device, and a connection between said movable member and said operating device, said connection including an operating member, a stop member movably connected to said operating member, and means for securing said operating member and said stop member together for simultaneous movement under normal conditions but for independent movement under abnormal conditions, said operable member ceasing its movement when the other member acts.

3. A stop motion mechanism including a member movable to stop operation of a machine, an operating device, and a connection between said movable member and said operating device, said connection including an operating member, a stop member movably connected with said operating member, and means for securing said operating member and said stop member together for simultaneous movement, said means being adapted to be ruptured on the application of abnormal forces in the operation of the mechanism, said operable member ceasing its movement when the other member acts.

4. A stop motion mechanism including a member movable to stop operation of a machine, an operating device, and a connection between said movable member and said operating device, said connection including an operating member, a stop member pivotally mounted on said operating member, and means for securing said stop member to said operating member for simultaneous movement thereof, said means being adapted to be ruptured on the application of abnormal forces thereto to thereby permit pivotal movement of the stop member on the operating member.

5. A stop motion mechanism including a member movable to stop operation of a machine, an operating device, and a connection between said movable member and said operating device, said connection including an operating member, a stop member movably connected to said operating member, and means for securing said operating member and said stop member together for simultaneous movement under normal conditions but for permitting independent movement 103 under abnormal conditions, and a connecting member movable independently of said movable member and also simultaneous therewith for stopping operation of the machine.

6. A stop motion mechanism including a member movable to stop operation of a machine, an operating device, and a connection between said movable member and said operating device, said connection including a member operable independently of said movable member under normal conditions of operation of the machine, and means for imparting excessive movement to said independently operable member to effect movement of said movable member.

7. A stop motion mechanism including a member movable to stop operation of a machine, an operating device and a connection between said movable member and said operating device, said connection including a member having a lost motion and thereby operable independently of said movable member under normal conditions of operation of the machine, and means for causing said member to move in excess of said lost motion and thereby effect operation of said movable member to stop operation of the machine. 45
- 5 8. A stop motion mechanism including a member movable to stop operation of a machine, an operating device and a connection between said movable member and said operating device, said connection including an operating member, a stop member movably connected to said operating member, means for securing said operating and said stop members together for simultaneous movement under normal conditions, means for severing said connection under abnormal conditions, and a connecting member operated by said stop member and having a normal movement independently of said movable member and an excessive movement caused by the severing of said connection whereby operation of said movable member to stop operation of the machine is effected. 50
- 10 9. A stop motion mechanism including a member movable to stop operation of a machine, an operating device, and a connection between said movable member and said operating device, said connection including an operating lever, a stop member mounted on said lever to move independently thereof, means for securing the stop lever to said member for simultaneous movement therewith under normal conditions but to permit said independent movement under abnormal conditions, and a link connected with said stop member and having a movement independently of said movable member under normal conditions of operation and an excessive movement caused by the independent movement of said stop member whereby said movable member is operated to stop the machine. 55
- 15 10. A stop motion mechanism including a member movable to stop operation of the machine, an operating device, and a connection between said movable member and said operating device and including a member having a definite range of movement under normal conditions and a member to change said range of movement under abnormal conditions and thereby cause operation of said movable member to stop the machine. 60
- 20 11. A stop motion mechanism including a member movable to stop operation of the machine, an operating device, and a connection between said movable member and said operating device and including a member having a certain range movement under normal conditions and a member adapted to be ruptured upon undue resistance to movement of said operating device and thereby increase said range of movement to effect movement of said operating member to stop the machine. 65
- 25 12. A stop motion mechanism including a stopping member movable to stop operation of the machine, an operating device, an operated member, and a connection between said stopping member and said operating device, said connection including means secured to said operated member and operable independently of said stopping member under abnormal conditions and a member adapted to be ruptured under abnormal conditions to effect movement of said means independently of said operated member to operate said stopping member to stop the machine. 70
- 30 75
- 35 80
- 40
